UNITED STATES PATENT OFFICE.

SAMUEL H. BECK, OF NEW YORK, N. Y.

ELECTRIC SWITCH.

No. 808,065.

Specification of Letters Patent.

Patented Dec. 26, 1905.

Application filed April 22, 1905. Serial No. 256,831.

To all whom it may concern:

Be it known that I, SAMUEL H. BECK, a citizen of the United States of America, and a resident of the borough of Brooklyn, city, county, 5 and State of New York, have invented certain new and useful Improvements in Electric Switches, of which the following is a specification.

My invention relates generally to electric 10 switches, and has more particular reference to switches controlled by fluid-pressure.

My invention is used in connection with a motor for keeping a constant pressure in a reservoir for beer or the like. As the beer 15 or other beverage is drawn off from its tank the pressure therein decreases *pari passu*. When this pressure falls to a certain point, the motor must be started up to again increase the pressure to a proper amount. When 20 the proper pressure is reached, it is necessary to throw the motor off. The means for starting or stopping the motor are preferably automatic and controlled by fluid-pressure in the reservoir. The switch for making and breaking 25 must act instantaneously, so that no sparking is produced. I have endeavored to invent an automatic electric switch controlled by the pressure in the reservoir, which shall most advantageously embody these desired characteristics.

Other features of my invention will appear as the specification proceeds.

In the accompanying sheet of drawings I have illustrated my invention in a preferred 35 form, although it will of course be understood that changes in arrangement or structure of parts may be made without departing from the spirit of my invention.

In the various figures I have indicated like 40 parts by like numerals of reference.

In the drawings, Figure 1 is a cross-sectional view of my switch with the blade shown in its make position. Fig. 2 is a similar view, parts being omitted, showing the blade in its 45 break position. Fig. 3 is an end elevation showing the manner in which I attach the switch to the cylinder. Fig. 4 is a diagrammatic view showing the motor, compressor, reservoir, and electric and pneumatic connections.

From the reservoir containing the beer or other beverage the pipe 1 leads to the cylinder 2, across which is stretched at a suitable point and secured in a proper manner the diaphragm 3, of flexible material. Working in 55 the cylinder is the plunger 4, having a collar

5, provided with a threaded passage 6, with which the plunger engages. The head of the plunger rests against the diaphragm, thereby enabling the latter to move the plunger when 60 the pressure thereon exceeds a certain amount. The spring 8, mounted in the cylinder, presses against the collar and holds the plunger against the diaphragm. Its tension may be varied by suitable means, such as the thumb-screw 9, engaging with the interior threaded portion 10 of the cylinder, the spring being seated on the thumb-screw. The passage 11 is formed in a thumb-screw through which the plunger 6 passes, so that it may be adjusted in regard to its 65 pressure upon the diaphragm without disconnecting the parts. Properly secured to the outside of the cylinder is the base 12, consisting of a non-combustible insulating material. Secured to the base are the clips 13 and 14, forming electrodes, and from which the wires 15 and 16 lead to the motor. On a bracket 17, secured to the outer surface of the cylinder, is a movable member or blade 18, pivoted on the bracket at 19 and adapted to make and 70 break with the electrodes. As before intimated, it is necessary that the make and break of the blade with the clips take place instantaneously. I accomplish this by the following means: Mounted on the pivot 19 is an actuating member—in this instance in the form of two bell-cranks 20 connected by means of the two cross bars or pins 21 and 22. A spring 23 is connected at one end to the movable member or blade and at its other end to the 75 actuating member—in this case to the pin 24—at a point beyond the pivotal center 19 of the blade. It will readily be understood that as the actuating member is moved it carries or throws the spring from one side of the pivotal center of the blade to the other, making or 80 breaking contact instantaneously, as the case may be. The actuating member may be moved by any suitable means, but is preferably controlled in its movement by the amount of fluid-pressure acting on the diaphragm. In the present instance I move it by means of the pin 25, secured to the collar of the plunger and passing through the slot 26, formed in the cylinder and adapted to contact with the cross-bars of the actuating member, so as to rotate 85 the latter in one direction or the other, according as the plunger is ascending or descending.

The motor is indicated by 27 and operates the compressor 28, connected with the reservoir 31 by the tube 29.

30 indicates the electric connections running

from the switch and which receive their supply from the battery 32.

The switch operates as follows: The pressure having decreased to a certain point, the 5 blade will be in contact with the clips, as shown in Fig. 1, and the motor started. The action of the latter increases the pressure in the reservoir, and thereby tends to raise the diaphragm from the position shown in Fig. 1. 10 The diaphragm when moved carries with it the plunger, and the pin secured to the latter acts to rotate the actuating member until the latter in its rotation throws the spring over the pivotal center of the blade and instantaneously 15 breaks its contact with the clips. The motor is then stopped, and as the beer or other beverage is drawn off the pressure decreases, allowing the spring 8 to depress the plunger. The pin connected to the plunger then moves 20 the actuating member, as indicated by the arrow in Fig. 2, until the spring is thrown over the pivotal center of the blade and the latter thereby instantaneously brought into contact with the clips or electrodes, starting the motor. 25

What is claimed is—

1. In an electric switch: the combination with stationary electrodes, of a movable member pivoted at one end, a reciprocating, fluid- 30 actuated member, a bell-crank for operating the movable member loosely pivoted, a spring connected at one end with the movable member and at its other end with the bell-crank at a point beyond the pivotal center of the movable member, pins on the bell-crank, and a pin carried by the fluid-actuated member adapted to contact with the pins on the bell-crank to move the same.

2. In an electric switch: the combination 40 with stationary electrodes, of a movable member pivoted at one end, a reciprocating, fluid-actuated member, a bell-crank for operating the movable member loosely pivoted and having a portion extending to a point beyond the 45 pivotal center of the movable member, a spring connected at one end with the movable member and at its other end with said portion of the bell-crank at a point beyond the pivotal center of the said movable member, pins 50 on the bell-crank, and a pin carried by the fluid-actuated member adapted to contact with the said pins on the bell-crank for moving the same.

3. In an electric switch, the combination 55 with stationary electrodes, of a cylinder, a fluid-actuated plunger reciprocating therein, a shaft mounted at the side of said cylinder, a movable member pivoted to said shaft and adapted to make and break contact with the 60 electrodes, an actuating member mounted on said shaft, a spring connected at one end to the movable member and at the other end to the actuating member at a point beyond the pivotal center of the movable member, and 65 means carried by the plunger adapted to move

the actuating member to throw the spring over the pivotal center of the movable member.

4. In an electric switch, the combination with stationary electrodes, of a cylinder, a fluid-actuated plunger reciprocating therein, a shaft mounted at the side of the cylinder, a movable member pivoted on the shaft and adapted to make and break contact with the electrodes, a bell-crank mounted on said shaft, 70 a spring connected at one end to the movable member and at its other end to the bell-crank at a point beyond the pivotal center of the movable member, and means carried by the plunger adapted to move the bell-crank to throw the spring over the pivotal center of the movable member at predetermined points in the reciprocation of the plunger. 75

5. In an electric switch, the combination with stationary electrodes, of a cylinder, a fluid-actuated plunger reciprocating therein, a shaft mounted at the side of the cylinder, a movable member pivoted on the shaft and adapted to make and break contact with the electrodes, a bell-crank mounted on said shaft, 80 a spring connected at one end to the movable member and at its other end to the bell-crank at a point beyond the pivotal center of the movable member, and a pin carried by the plunger adapted to move the bell-crank to throw the spring over the pivotal center of the movable member at predetermined points in the reciprocation of the plunger. 85

6. In an electric switch, the combination with a pair of clips forming stationary electrodes, of a cylinder, a fluid-actuated plunger reciprocating therein, a shaft mounted at the side of the cylinder, a blade pivoted on said shaft and adapted to make and break contact with the electrodes, a bell-crank mounted on 100 said shaft, a spring connected at one end to the blade and at the other end to the bell-crank at a point beyond the pivotal center of the blade, and a pin carried by the plunger adapted to move the bell-crank at 95 predetermined points in the reciprocation of the plunger to throw the spring over the pivotal center of the movable member. 110

7. In an electric switch, the combination with stationary electrodes, of a cylinder, a fluid-actuated plunger reciprocating therein, a shaft mounted at the side of said cylinder, a movable member pivoted on the shaft, a bell-crank mounted on said shaft for operating the movable member, a spring connected at 115 one end with the movable member and at its other end with the bell-crank at a point beyond the pivotal center of the movable member, a pin on the bell-crank, and a pin carried by the plunger adapted to coact with said pin 120 on the bell-crank to move the latter. 125

8. In an electric switch, the combination with a cylinder, of a plunger having a collar through which it extends and with which it is in threaded engagement, said collar carry- 130

ing means for operating the switch, a diaphragm adapted to move the plunger, a spring seated on the collar and adapted to press the plunger against the diaphragm, and means for regulating the tension of the spring.

9. In an electric switch, the combination with a cylinder, of a plunger operating therein and provided with a collar-carrying means adapted to operate the switch, a diaphragm adapted to move the plunger, a spring adapted to press the plunger against the diaphragm, a thumb-screw engaging with an interiorly-threaded portion of the cylinder and adapted to regulate the tension of the spring, and means adapted to adjust the plunger with relation to the diaphragm.

10. In an electric switch, the combination with a cylinder, of a plunger operating therein, having a collar-carrying means adapted to operate the switch, a diaphragm, a spring seated on the collar and adapted to press the plunger against the diaphragm, a thumb-screw engaging with an interiorly-threaded portion of the cylinder and adapted to regulate the tension of the spring, said thumb-

screw being provided with a threaded passage for the stem of the plunger, and the latter having a threaded portion engaging with the threaded passage in the collar whereby the plunger is adjusted with relation to the diaphragm.

11. In an electric switch, the combination with a cylinder, of a plunger carrying a collar provided with means adapted to operate the switch and with which the plunger is in threaded engagement, a diaphragm adapted to move the plunger, a spring seated on the collar, a thumb-screw in engagement with an interiorly-threaded portion of the cylinder and adapted to regulate the tension of the spring, said plunger extending through the spring and thumb-screw whereby the said plunger can be adjusted with relation to the diaphragm independently of the thumb-screw.

Signed at New York city this 19th day of April, 1905.

SAMUEL H. BECK.

Witnesses:

RAYMOND C. SPAULDING,
FRED. BEEKEN.

It is hereby certified that in Letters Patent No. 808,065, granted December 26, 1905, upon the application of Samuel H. Beck, of New York, N. Y., for an improvement in "Electric Switches," errors appear in the printed specification requiring correction, as follows: On page 3, in lines 8 and 19, the hyphens between the words "collar" and "carrying" should be stricken out; and that the said Letters Patent should be read with these corrections therein that the same may conform to the record of the case in the Patent Office.

Signed and sealed this 30th day of January, A. D., 1906.
